UNITED STATES PATENT OFFICE.

WINSTON KENT PENDLETON, OF OCOEE, FLORIDA, ASSIGNOR OF TWO-
THIRDS TO WILLIAM PENDLETON BLAKELY AND WILLIAM STRICKLER
JONES, OF SAME PLACE.

THILL-COUPLING.

SPECIFICATION forming part of Letters Patent No. 659,099, dated October 2, 1900

Application filed November 11, 1899; Renewed August 27, 1900. Serial No. 28,246. (No model.)

To all whom it may concern:

Be it known that I, WINSTON KENT PENDLETON, of Ocoee, in the county of Orange and State of Florida, have invented a new and useful Improvement in Thill-Couplings, of which the following is a specification.

My invention is an improvement in thill-couplings, and has for its object a device of this character which will be of comparatively few parts, easy to attach or detach from the axle, and with which the shaft or pole may be quickly and securely coupled and easily uncoupled.

The invention consists in certain details of construction and arrangement of the parts, which will be hereinafter described and claimed.

Reference is to be had to the accompanying drawings, forming part of this specification, in which like characters of reference indicate corresponding parts in all the views.

Figure 1 is a rear perspective view of my improved thrill-coupling. Fig. 2 is a transverse section thereof. Fig. 3 is a detail view of bolt employed. Fig. 4 is a detail perspective view of the locking-lever. Fig. 5 is a similar view of the locking-nut. Fig. 6 is a perspective view of the shackle. Fig. 7 is a similar view of the clip, and Fig. 8 is a similar view of the pivot-pin.

The shackle 10 consists of a base-plate 11 and spaced-apart jaws 12, preferably formed of one integral piece of suitable metal. Near its rear end the base-plate is formed with an aperture 13, through which the lower threaded end of a cam-bolt 14 is arranged to loosely extend, said bolt at its upper end being provided with a notch forming a shoulder 15, with which is adapted to engage the rear apertured end 16 of the metal clip 17. This clip 17 extends forwardly over the upper part of the axle A, as shown in Figs. 1 and 2, and at its front end is formed with preferably-integral apertured ears 18, adapted to engage with the upper recessed ends 19 of the jaws 12 and with a spring extension 20, extending downwardly between said jaws, for a purpose to be hereinafter explained.

On the threaded lower end of the bolt 14 screws a nut 21, having trunnions 22 inserted

in suitable bearings in the bifurcated end of a locking-lever 23, said lever having cam-surfaces 24, adapted to ride on the lower face of the base-plate and lock the shackle securely to the axle A when the locking-lever is turned up into the position shown in Fig. 1, the arm of said lever in such position entering a recess 25 in the rear edge of the base-plate. By this means the shackle is quickly secured on the axle and may be quickly and easily detached therefrom. 55 60

The shaft or pole B is formed with a non-circular opening B' in its rear end, into which is inserted the flattened shank of the pivot-pin 26, formed at one end with an integral oblong or flattened head 27 and screw-threaded at its other end to receive a second oblong head 28. The rear end of the shaft or pole, with the pivot-pin 26 attached, is inserted between the jaws 12 in a vertical position, and the heads 27 and 28 enter vertical passages 29 in the jaws, of a width about equal to the shortest diameter of the heads, the said passages being widened at the bottom to form bearings 30, of a shape approximating the 75 contour of the heads. The free end of the shaft or pole is then lowered into working position, when, it will be seen, it is securely held from withdrawal, while the necessary play is permitted, for it cannot be removed 80 from the bearings 30 until it is held vertical.

The spring-extension 20 of the clip 17 bears against the rear extremity of the thill, as shown in Fig. 2, thereby forming an anti-rattler.

Having thus described my invention, what I claim as new, and desire to secure by Letters Patent, is—

1. A thill-coupling, consisting of jaws adapted to hold the pole or shaft and having recesses at their upper ends, a base-plate adapted to extend underneath the axle and connected with said jaws and having an aperture near its rear end, a bolt extending loosely through said aperture, a clip engaging said bolt and adapted to extend over the axle, the said clip being provided with ears arranged to enter the recesses in the jaws, and means for locking said bolt, as set forth. 90 95

2. In a thill-coupling, the combination of 100

- the jaws and base-plate, a clip arranged for engagement with the jaws at one end, a bolt connected to said clip at its other end and extending through the base-plate, a nut screwing on the lower end of said bolt and formed with trunnions, and a locking-lever mounted on said trunnions and having cam-surfaces adapted to ride on the lower face of said base-plate, as set forth.
5. A thill-coupling, comprising a base-plate and thill-holding jaws, which latter are formed with recesses at their upper ends, a clip adapted to rest on the axle and having ears arranged to enter said recesses, and a connection between the rear of the base-plate and the rear of the clip, as and for the purpose set forth.
10. 3. A thill-coupling, comprising a base-plate and thill-holding jaws, which latter are recessed at their upper ends, a clip provided with apertured ears at its front end adapted to enter said recesses, and an apertured rear end, and a notched bolt detachably connected to the base-plate and engaging the apertured rear end of the clip, as set forth.
15. 4. A thill-coupling, comprising a base-plate and thill-holding jaws, which latter are recessed at their upper ends, a clip provided with apertured ears at its front end adapted to enter said recesses, and an apertured rear end, and a notched bolt detachably connected to the base-plate and engaging the apertured rear end of the clip, as set forth.

5. A thill-coupling, consisting of spaced-apart jaws adapted to receive the pole or shaft, and a base-plate adapted to extend underneath the axle, and a clip arranged for connection to the rear of the base-plate and having apertured ears adapted to engage the upperends of said jaws and an extension beyond said ears, said extension forming an antirattler, as set forth.

6. In a thill-coupling, the combination with the jaws having vertical passages enlarged at their lower ends, of a pole or shaft having a non-circular or flattened opening in its rear end, and a pivot-pin having a correspondingly-shaped shank fitted in said opening, and a fixed flattened head and a detachable flattened head on said shank adapted to be inserted in said passages, as set forth.

In testimony whereof I have signed my name to this specification in the presence of two subscribing witnesses.

WINSTON KENT PENDLETON.
